UNITED STATES PATENT OFFICE.

WILLIAM W. JACKSON, OF PHILADELPHIA, PENNSYLVANIA, ASSIGNOR TO
MACKELLAR, SMITHS & JORDAN, OF SAME PLACE.

DESIGN FOR A FONT OF PRINTING-TYPES.

SPECIFICATION forming part of Design No. 11,789, dated May 25, 1880.

Application filed April 28, 1880. Term of patent 14 years.

To all whom it may concern:

Be it known that I, WILLIAM W. JACKSON, of the city and county of Philadelphia, Pennsylvania, (assignor to MacKellar, Smiths & Jordan,) have invented and produced a new and original Design for a Font of Printing-Types, of which the following is a specification.

The nature of my design is clearly shown in the accompanying typographic impression, to which reference is made.

It consists of a back-hand script letter as distinguished from a running-hand script letter, the outline of which letter consists of the heavy part shaded upon the right by a light line and upon the left by a light line, the space between which and the heavy part is shaded by a series of light horizontal lines, as shown.

In the capital letters A, B, F, I, J, M, N, P, R, S, T, and Y the lower left-hand termination is ball-shaped, the face of which is shaded by a series of light horizontal lines.

In the letter A the cross-portion of the letter gradually widens from right to left, and curves outward beyond the left-hand portion of the letter.

In the letter B the lower right-hand portion of the letter extends below the left-hand portion of the letter and curves to the left.

The upper portion of the C curves inward to the left, and its lower portion curves to the right.

The upper and lower portions of the E form a loop about centrally.

The cross-portion of the F is formed by a short inclined line upon the left, and upon the right by a short curved line terminating in a ball.

In the G the lower portion of the letter crosses the lower portion of the body of the letter, forming a loop, as shown, and the upper right termination curves inward toward the left.

In the H the right-hand portion of the let-

ter projects below the left-hand portion and curves to the right.

In the K the ball termination is found in the upper right-hand corner, and the lower right termination extends below the left-hand portion of the letter.

In the letter L the lower portion of the letter is scroll-shaped.

In the letter N the ball termination is also found at the upper right hand.

In the letters O and Q the left-hand upper portion of the letters curves to the right and above the right-hand upper portion of the letters.

In the letter R the lower right-hand portion of the letter projects below the left-hand portion.

The upper portion of the letter S has the pennated-like ornament upon the left.

In the letters U, V, W, X, and Y the upper left-hand portion curves as shown, and in the V and X the ball-like termination is found at the upper right hand.

Both terminations of the Z are curved, as shown.

In the lower-case letters and in the figures the character of the design is preserved, the ball termination being found in the f, k, r, s, and x, and the curved termination in the o, v, w, and figure 2. The upper right portion of the figure 4 gradually widens and curves, the curved termination characterizes the lower portion of the figures 3, 5, and 9, and the lower portion of the figure 7 gradually widens.

Having now set forth my invention, what I claim as new is—

The design for a font of printing-types, as shown and described.

WM. W. JACKSON.

In presence of—
C. G. HUCH,
H. METIUS.
